US00D980728S

(12) **United States Design Patent** (10) **Patent No.:** **US D980,728 S**
(45) **Date of Patent:** **** Mar. 14, 2023**

(54) **COVER FOR TRACKING DEVICE**

(71) Applicant: **ELAGO COMPANY CO., LTD.**,
Goyang-si (KR)

(72) Inventor: **Chanwoo Lee**, Goyang-si (KR)

(73) Assignee: **ELAGO COMPANY CO., LTD.**,
Goyang-si (KR)

(**) Term: **15 Years**

(21) Appl. No.: **29/800,293**

(22) Filed: **Jul. 20, 2021**

(51) LOC (14) Cl. **10-04**
(52) U.S. Cl. **D10/74**

(58) **Field of Classification Search**

USPC D10/121, 38, 32, 31, 70, 104.1, 106.1;
D14/203.5, 203.1, 203.6, 344, 471, 385;

(57) **CLAIM**

The ornamental design for a cover for tracking device, as shown and described.

DESCRIPTION

FIG. 1 is a front, top, and right side perspective view of a cover for tracking device, showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged sectional view thereof taken in the direction of line 8-8 shown in FIG. 6;

FIG. 9 is a rear, bottom, and right side perspective view thereof; and,

FIG. 10 is a rear, top, and left side perspective view thereof in use.

The long dash short dash broken lines and arrows shown in FIG. 6 are used to identify the sectional view and form no part of the claimed design. The evenly spaced oblique parallel broken lines in FIG. 8 represent hatching lines and form no part of the claimed design. The evenly spaced broken lines shown in FIGS. 1-10 depict parts of the cover for tracking device or environment and form no part of the claimed design.

1 Claim, 7 Drawing Sheets
